CLOTHES HANGER

Carl F. Brinkman, Milwaukee, Wis.

Application March 29, 1946, Serial No. 657,961

2 Claims. (Cl. 223—96)

1

The present invention relates to coat hangers and more particularly to a novel clothes hanger adapted to suspend a coat and two pairs of trousers.

An object of the invention is to provide a device which will include springless means for separate hanging of two pairs of trousers and a removable coat hanging element.

Other and further objects of the invention will appear as the description proceeds, reference being had to the accompanying drawing, in which—

Fig. 1 is a view in perspective of a clothes hanger embodying my invention.

Fig. 2 is an end view of the same unlatched.

Fig. 3 is a plan view of the detachable coat hanger.

Fig. 4 is an edge view of the same.

Fig. 5 is an edge view of the detachable coat hanger in folded position.

Fig. 6 is a side view in elevation of the clothes hanger showing the detachable coat hanger in place.

Referring more in detail to the drawing, the numeral 10 refers to the device generally having a central bar 11, rigidly connected with a wire frame 12, which latter has a U-shaped dip 13 in the top thereof. A hanger hook 14 has a bifurcated lower end 15, the terminals of which are bent to form eyes 16, which engage pivotally around the lower segment 17 of the U-shaped bend in frame 12. A bend occurs at 18 of the end 15, for a purpose which will be later described. A wire latch 19 is fastened by eyes 20 to the segment 17 by the ends in a manner similar to that of eyes 16. This latch has a bend at 21 thereof, also for a purpose which will be later described.

A pair of moveable outer bars 24 and 25 are provided, and each bar has an auxiliary frame member 26 and 27 constituting a single piece of wire attached to bar 25, at 28 and 29 thereof and with its upper end bent around the top of frame 12 and thereunder to form a short arm lever 26a for the latch 19. The auxiliary frame 27 is bent similarly to provide a short arm lever 27a forming a keeper for the bend 18 in the hook shank 15. It will be seen that when the hook 14 is pulled to an upright position, the bend 18 will engage with the short arm lever 26a pressing it inwardly of the device and causing the outer bar 24 to press firmly against the inner or central

2

bar 11, or anything held therebetween. Similarly when the latch 19 is pulled downwardly, its bend 21 engages to secure inwardly the lever portion 27a of the upper portion of auxiliary frame 27, thus forcing by pressure against said lever 27a, the outer bar 27 against the central bar 11.

A detachable coat hanger includes a central segment 30 and a rectangular opening at 31 thereof, the corners of which are rotundly indented as at 32 to receive the round contours of frames 26 and 27 as shown in Fig. 6. Pivotaly attached to the central segment 30, at 33 and 34 thereof are the shoulder supports 35 and 36, one 15 on either face of said segment.

The detachable coat hanger may be compactly folded as shown in Fig. 5.

It will be understood that the device is capable of many modifications in structure and design, 20 without departing from the spirit of the invention, within the scope of the appended claims.

Having thus described my invention, what I claim and desire to secure by Letters Patent of the United States is:

25 1. In a device of the class described, a trouser hanger, a hanger hook for the same, substantially vertical wire frame members connecting the hook and the body of the hanger, a supplementary hanger comprising a plurality of plates pivoted 30 interconnectedly at their ends and adapted to fold substantially on a plane, the center plate having a rectangular opening centrally therein adapted to engage about the said rods.

2. In a device of the class described, a trouser hanger, a hanger hook for the same, substantially vertical wire frame members connecting the hook and the body of the hanger, a supplementary hanger comprising a plurality of plates pivoted 35 interconnectedly at their ends and adapted to fold substantially on a plane, the center plate having a rectangular opening centrally therein with cut out portions at the corners thereof adapted to receive the said rods.

CARL F. BRINKMAN.
